[57] CLAIM

The ornamental design for a door panel or the like, as shown and described.

DESCRIPTION

FIG. 1 is a perspective view of a door panel or the like showing my new design;

FIG. 2 is a front elevational view thereof;

FIG. 3 is a rear elevational view thereof;

FIG. 4 is a side elevational view, the opposite side being a mirror image thereof;

FIG. 5 is a top plan view thereof;

FIG. 6 is a bottom plan view thereof;

FIG. 7 is a perspective view of a second embodiment of a door panel or the like showing my new design;

FIG. 8 is a front elevational view of the embodiment of FIG. 7;

FIG. 9 is a rear elevational view of the embodiment of FIG. 7;

FIG. 10 is a side elevational view of the embodiment of FIG. 7, the opposite side being a mirror image thereof;

FIG. 11 is a top plan view of the embodiment of FIG. 7;

FIG. 12 is a bottom plan view of the embodiment of FIG. 7;

FIG. 13 is a perspective view of a third embodiment of a door panel or the like showing my new design;

FIG. 14 is a front elevational view of the embodiment of FIG. 13;

FIG. 15 is a rear elevational view of the embodiment of FIG. 13;

FIG. 16 is a side elevational view of the embodiment of FIG. 13, the opposite side being a mirror image thereof;

FIG. 17 is a top plan view of the embodiment of FIG. 13; and,

FIG. 18 is a bottom plan view of the embodiment of FIG. 13.
